UNITED STATES PATENT OFFICE.

HERBERT R. KELLS, OF LOS ANGELES, CALIFORNIA.

DESIGN FOR A VEHICLE-SIGNAL.

47,235.

Specification for Design.

Patented Apr. 13, 1915.

Application filed April 30, 1914. Serial No. 835,571. Term of patent 7 years.

To all whom it may concern:

Be it known that I, HERBERT R. KELLS, a citizen of the United States, residing at Los Angeles, in the county of Los Angeles and State of California, have invented a new, original, and ornamental Design for a Vehicle-Signal, of which the following is a specification, reference being had to the accompanying drawing, forming part thereof.

Figure 1 is a front elevation of a vehicle

signal, showing my new design. Fig. 2 is a side elevation of the design.

I claim:

The ornamental design for a vehicle signal, as shown.

HERBERT R. KELLS.

Witnesses:

G. T. HACKLEY,
LORA M. BOWERS.
